DESIGN FOR AN APPARATUS FOR A GAME OF SKILL

De Hart G. Scrantom and Lewis H. Nyhagen,
Maplewood, N. J.

Application June 20, 1935, Serial No. 57,357

Term of patent 3½ years

To all whom it may concern:

Be it known that we, De Hart G. Scrantom and Lewis H. Nyhagen, citizens of the United States of America, residing at Maplewood, in the county of Essex and State of New Jersey, respectively, have invented a new, original, and ornamental Design for Apparatus for a Game of Skill, of which the following is a specification, reference being had to the accompanying drawing, forming a part thereof, in which the figure is a perspective view of an apparatus for a game of skill, showing our new design.

We claim:

The ornamental design for an apparatus for a game of skill as shown.

In witness whereof, we hereunto subscribe our names this 13th day of June, 1935.

LEWIS H. NYHAGEN.
DE HART G. SCRANTOM.
